DESIGN FOR A HUMIDIFIER

Gertrude M. Hogan, New York, N. Y.

Application May 29, 1933. Serial No. 48,233

Term of patent 3½ years

To all whom it may concern:

Be it known that I, GERTRUDE M. HOGAN, a citizen of the United States, residing at New York, in the county of New York and State of New York, have invented a new, original, and ornamental Design for a Humidifier, of which the following is a specification, reference being had to the accompanying drawing, forming part thereof.

The figure is a perspective view of a humidifier showing my new design.

The two other sides, not shown, are ornamented in the same way as shown on the drawing. The bottom is not ornamented.

I claim:

The ornamental design for a humidifier as shown and described.

GERTRUDE M. HOGAN.
